UNITED STATES PATENT OFFICE.

JOHN OLOF LINDEN, OF ALBUQUERQUE, NEW MEXICO.

MASSAGE DEVICE.

Application filed September 13, 1921. Serial No. 500,332.

To all whom it may concern:

Be it known that I, JOHN O. LINDEN, a citizen of the United States, and a resident of Albuquerque, in the county of 5 Bernalillo and State of New Mexico, have invented a new and Improved Massage Device, of which the following is a full, clear, and exact description.

This invention relates to improvements in 10 massage devices, particularly to devices of the general character disclosed in Letters Patent of the United States, No. 1380986, issued to me on June 7, 1921, and in my co-pending application, Serial No. 492,080.

15 An object of this invention is to provide a massage device adapted to receive temperature regulating agents and to provide means for protecting the hands of the user from being injured by the temperature regulating agents.

20 A further object is to provide a massage device of simplicity and durability in construction, which will be efficient in use, which may be cheaply manufactured, and 25 which will be neat and attractive in appearance.

With these and other objects in view the invention consists in certain novel features of construction, and combinations and arrangements of parts as will be more fully hereinafter described and pointed out in the 30 claims.

In the accompanying drawings—

Figure 1 is a view in side elevation of my 35 improved massage device with the parts broken away for clearness.

Figure 2 is a top plan view of the device with the parts broken away for clearness.

Figure 3 is a view in transverse section 40 on the line 3—3 of Figure 2.

Referring in detail to the drawings, my improved device comprises a substantially oval-shaped, cup-like receptacle 1. The open upper end of the receptacle may be 45 closed by a chambered cover, such as 2. The cover 2 is formed in two pieces, the cover bottom 3 being bent to provide a peripheral channel, such as 4, in which a gasket 5 is located. This gasket may be either of cork, 50 rubber, or other suitable material.

The cover top 6 is spaced from the intermediate portion of the cover bottom 3 and is permanently secured to the upwardly presented channeled periphery of the bottom 55 3. The two cover sections may be

joined in any approved manner such as welding, soldering, or riveting.

The gasket 5 rests upon the upper edge of the container 1 and the upper cover section 6 is formed with flaring beaded edges 7 60 which depend and embrace the upper end of the receptacle.

A depending apron 8 is made integral with the upper cover 6 at each side of the container. The aprons are slotted as indicated at 9, and bent outwardly as shown at 10, to receive outstruck lugs 11 formed in the sides of the container 1. The lugs 11 project into the offset portions 10 of the aprons and are engaged by the portions of 70 the aprons located below the slits 9 to positively lock the cover in position on the receptacle.

It will be noted that the upper cover section 6 and the aprons 8 are spaced from the 75 walls of the receptacle throughout their entire length. The cover sections 6 and 3 provide between them an air or vacuum chamber 12 which prevents the transmission of heat or cold through the cover. 80

In using the device the container 1 is filled with temperature regulating agents and the user grasps the two aprons 8 with his thumb and fingers, the palm of his hand resting upon the cover 6. By virtue of the construction above-described, the massage device may be used without discomfort to the hands and without danger of spilling the contents of the container, the bottom 13 of 90 which forms a massaging surface. 90

Although I have illustrated one of the preferred embodiments of the invention, it will be apparent that various slight changes might be made in the general form and arrangement of the parts described without departing from the invention, and hence I do not limit myself to the precise details set forth, but consider myself at liberty to make such changes and alterations as fairly fall within the spirit and scope of the appended claims. 100

I claim:

1. A massage device, comprising an open top receptacle, and a chambered cover closing said receptacle, said cover being locked 105 to the receptacle and provided at its sides with means for protecting the hands of the user.

2. A massage device, comprising an open top receptacle, a chambered cover closing 110

said receptacle, and depending aprons carried by the cover and spaced from opposite sides of the container, said aprons serving to protect the hands of the user.

5 3. A massage device, comprising an open top receptacle, a chambered cover closing said receptacle, depending aprons carried by the cover and spaced from opposite sides of the container, and means integral with 10 the container engageable with the aprons to prevent removal of the cover.

4. In a massage device, an open top receptacle, a hollow cover normally closing said receptacle, said cover including a lower 15 section bent to provide a peripheral channel, a gasket in the channel bearing against the upper edge of the receptacle, and an upper cover section secured to the periphery of the first-mentioned section and spaced from the 20 intermediate portion thereof.

5. In a massage device, an open top receptacle, a hollow cover normally closing said receptacle, said cover including a lower 25 section bent to provide a peripheral channel, a gasket in the channel bearing against the upper edge of the receptacle, an upper cover section secured to the periphery of the first-mentioned section and spaced from the intermediate portion thereof, and depending 30 aprons integral with the upper cover section and spaced from opposite sides of the container.

6. In a massage device, an open top receptacle, a hollow cover normally closing 35 said receptacle, said cover including a lower section bent to provide a peripheral channel, a gasket in the channel bearing against the upper edge of the receptacle, an upper cover section secured to the periphery of the first-mentioned section and spaced from the intermediate portion thereof, depending aprons integral with the upper cover section and spaced from opposite sides of the container, 40 outstruck lugs formed in the walls of the container, and means associated with the aprons engageable with the lugs to lock the double cover in position.

7. A massage device, comprising an oblong receptacle, a cover having an air space 45 therein and provided at two opposite sides with aprons extending downwardly in spaced relation to the sides of the receptacle, and interlocking means on the receptacle and aprons for locking the cover on the receptacle.

8. In a massage device, a receptacle having outwardly extended struck-up lugs on opposite sides, and a cover for said receptacle having at opposite sides aprons extending downwardly in spaced relation to the sides 60 of the receptacle and having offset portions engaging the lugs of the receptacle.

JOHN OLOF LINDEN,
